UNITED STATES PATENT OFFICE

155,451

DESIGN FOR A LAMP WITH ILLUMINABLE BASE

Joseph Provenzano, New York, N. Y.

Application June 18, 1949, Serial No. 3,389

Term of patent 7 years

(Cl. D48—20)

To all whom it may concern:

Be it known that I, Joseph Provenzano, a citizen of the United States of America, residing in New York city, county of New York, and State of New York, have invented a new, original, and ornamental Design for a Lamp with Illuminable Base, of which the following is a specification, reference being had to the accompanying drawing, forming part thereof, wherein,

The characteristic features of my design reside in the portions shown in full lines in the drawing.

I claim:

The ornamental design for a lamp with illuminable base, substantially as shown and described.

JOSEPH PROVENZANO.
